(57) **CLAIM**

The ornamental design for a gaming machine with display, as shown and described.

DESCRIPTION

FIG. 1 is a front perspective view of a gaming machine with display showing our new design;

FIG. 2 is a front view of the gaming machine with display shown in FIG. 1;

FIG. 3 is a back view of the gaming machine with display shown in FIG. 1;

FIG. 4 is a left side view of the gaming machine with display shown in FIG. 1;

FIG. 5 is a right side view of the gaming machine with display shown in FIG. 1;

FIG. 6 is a top view of the gaming machine with display shown in FIG. 1;

FIG. 7 is a front perspective view of a gaming machine with display showing an alternative embodiment of our new design;

FIG. 8 is a front view of the gaming machine with display shown in FIG. 7;

FIG. 9 is a back view of the gaming machine with display shown in FIG. 7;

FIG. 10 is a left side view of the gaming machine with display shown in FIG. 7;

FIG. 11 is a right side view of the gaming machine with display shown in FIG. 7;

FIG. 12 is a top view of the gaming machine with display shown in FIG. 7;

FIG. 13 is a front perspective view of a gaming machine with display showing a further embodiment of our new design;

FIG. 14 is a front view of the gaming machine with display shown in FIG. 13;

(Continued)

FIG. 15 is a back view of the gaming machine with display shown in FIG. 13;

FIG. 16 is a left side view of the gaming machine with display shown in FIG. 13;

FIG. 17 is a right side view of the gaming machine with display shown in FIG. 13; and,

FIG. 18 is a top view of the gaming machine with display shown in FIG. 13.

In these drawings, the solid lines illustrate the claimed ornamental design, whereas the broken lines illustrate unclaimed environmental features and form no part of the claimed design.
